UNITED STATES PATENT OFFICE.

EUGENE W. CRANE, OF ADRIAN, MICHIGAN.

DESIGN FOR A CANDY-TRAY.

SPECIFICATION forming part of Design No. 34,065, dated February 12, 1901.

Application filed December 24, 1900. Serial No. 40,982. Term of patent 14 years.

To all whom it may concern:

Be it known that I, EUGENE W. CRANE, a citizen of the United States, residing at Adrian, in the county of Lenawee and State of Michigan, have invented and produced a new and original Design for Candy-Trays; and I do declare the following to be a full, clear, and exact description of the same, reference being had to the accompanying drawings, forming a part thereof.

My invention relates to designs for a candy-tray, which is illustrated in the accompanying drawings, in which—

Figure 1 is a perspective view, and Fig. 2 is a longitudinal sectional view, thereof.

My design consists of an oblong tray provided with the bottom *a*, the parallel sides *b*,

and the rear panel *c*. The sides *b* are curved upward from each end on their upper edges, the said upper edges being rounded, as illustrated. The rear panel *c* on its upper edge is tapered at each end and then curved inward, as clearly illustrated.

Having thus described my design, what I desire to secure by Letters Patent is—

The design for a candy-tray, substantially as herein shown and described.

In testimony whereof I affix my signature in the presence of two witnesses.

EUGENE W. CRANE.

Witnesses:

CLARKE E. BALDWIN,
JOHN F. WILCOX.
